UNITED STATES PATENT OFFICE.

LEON S. BRACH, OF EAST ORANGE, NEW JERSEY, ASSIGNOR TO L. S. BRACH MANUFACTURING CO., OF NEWARK, NEW JERSEY.

ELECTRIC LAMP.

Application filed June 5, 1925. Serial No. 35,441.

This invention relates to an electric lamp and as depicted in the drawings attached to and forming a part of the specification, it is illustrated as adapted to a railway lamp.

5 It is one of the objects of my invention to provide, particularly, in a railway lamp, means for housing the electric light bulb and its associated mounting and reflector so as to protect same from coal dust, gasses, 10 and circulation of air currents which all tend to impair the efficiency of the various parts, particularly, the reflector.

Another object of my invention is to provide a lamp in which the bulb can be readily 15 focused in the reflector and in which the focusing parts may be securely locked in position so that jars and vibration will not put the bulb out of focus.

Another object of my invention is to provide a unitary construction including a reflector and mounting for the same together with the lamp socket and adjusting means whereby the same may be assembled complete, independent of the housing in which 25 the unitary structure is to be placed.

Another object of my invention is to provide a solid substantial housing for the said unitary structure and to provide means within the housing whereby the unitary structure may be quickly mounted and adjusted.

These and other objects will be apparent to one skilled in this art after a study of the specification taken in connection with the 35 annexed drawings, in which—

Figure 1 is a front view of the complete lamp as constructed for railway purposes.

Figure 2 is a side view of Fig. 1 showing the means for mounting the lamp.

40 Figure 3 is a vertical sectional view on the line 3—3 of Fig. 1 but with the cover and body part broken and brought slightly together so as to get the view on the sheet.

Figure 4 is a view from the back of the 45 lamp with the casing cover removed.

Figure 5 is substantially a full size view of the bulb socket and associated mechanism, while

50 Figure 6 is an end view of Fig. 5.

Referring now to the details wherein like numbers refer to corresponding parts in the various views, 1 is a casing of any suitable

material having a cover 2 provided with lugs 3 between which a rod 4 is positioned thereby serving as a handle for the cover. 55 The casing is provided with a dowel pin 55 adapted to position the cover 2 over the front of the casing. The casing is also provided with a lug 5 having a hole therein to receive a pin 6 carried by a locking arm 7 60 pivoted at 8 to the cover 2. Preferably, the cover 2 is attached to the casing 1 as by a chain 9. The casing 1 is adapted to be mounted on any suitable support by means of two channel brackets 10 and 11, preferably integral with the casing 1. Set screws 12 are provided for locking the casing 1 to the supporting member. Carried on the front of the casing 1 is a transparent member 13, preferably glass, that is held in place 65 by a flange ring 14, the same being held in place in any satisfactory manner as by screws 16 and lock washers 17, suitable packing 15 being used to prevent breakage of the glass 13 as well as to make a dust and gas 70 proof joint between the ring 14 and the front of the casing 7. The interior of the casing 1 is provided with a fixed anchorage 75 which is in the form of a rib 18 having an upwardly projecting flange 19. At the top 80 of the casing a movable anchorage is provided comprising a lug 20 fastened to the casing 1, and between ears on the lug a threaded screw 21 is pivoted. The threaded screw 21 carries a washer 22 and wing nut 85 23. These two anchorages are provided for mounting within the casing 1, the unitary structure which will now be described.

The unitary structure comprises a shell 24 90 preferably of suitable metal within which is positioned a reflector 25 preferably of glass. The reflector 25 is held in position by an annular ring 26 which engages at 27 the outer edge of the reflector. Carried between the ring 26 and the outer rim 28 of the shell 95 is a suitable packing means, preferably in the form of a ring of good felt. The packing member 29 may be held to the rim 28 and ring 26 as by means of cotter pins 56. The packing 29 acts as a cushioning means 100 for engaging the inner wall of the casing 1 and the packing 29 preferably extends beyond the ring 26 and the rim 28 so as to be at least slightly compressed when the parts

are in the position as shown in Figure 3. When a glass reflector is used, I prefer to use suitable packing material 30 at the rear of the reflector between it and the shell 24. Attached to the shell, as by rivets 31, is a pair of arms or brackets 32 and 33. As illustrated in the drawing, multiple leaves are utilized for this purpose. ing hold of the yoke 41 and moving the complete yoke structure. The bracket members 32 and 33 have a certain amount of resilience so that when the unitary structure herein described is mounted within the casing, the effect is that of a spring pressed connection against the front of the lamp casing. While I prefer to assemble the packing

The brackets 32 and 33 are forked at each end, the lower bracket passing over the rib 18, see Fig. 4, and behind the flange 19, while the upper bracket 32 is adapted to receive the threaded screw or movable anchorage 21. The shell 24 has a projecting part 34 which is slotted so that the same may be compressed. I also prefer to use a reinforcing collar 35 which is also slotted to correspond to slots in the projection 34. Carried by the projection 34 and slidable with 20 in the reinforcing member 35 is an insulator 36 which is preferably tubular in form. Within the insulator 36 is a tubular socket member 37 having the usual bayonet slots at one end to carry a lamp bulb 38. Positioned 25 within the socket 37 is another insulator 39 which has a central passage therethrough to receive a lamp contact member 40, the same being slidable within the insulator 39. Carried on the outer end of the members 36 and 37 is a yoke 41 preferably of good insulating material. The yoke 41 is anchored to the members 36 and 37 and also the insulator 39 in any satisfactory manner as by a set screw 42. Carried on the yoke are two terminal 35 contact members 43 and 44. Fastened to the terminal 44 is a metallic connecting strip 45 which has a flange 46 extending slightly beyond the end of the insulator 36 and the annular space between the flange 46 and the 40 end of the socket 37 is filled with solder 47 thereby completing a connection from the terminal 44 to the lamp socket 37. The contact terminal 43 is provided with a spring contact member 48 which is forked at 49 to fit over the end 50 of the terminal 40, resting against a flange 51 on the member 40 thereby applying a small amount of pressure to the contact terminal 40 to hold the same against the central contact of the lamp bulb 55 38 to insure that the same is held in locked position in the socket member 37. In order to insure a good contact to the member 40, I preferably provide a flexible stranded conductor 52 between the terminal 43 and the end 51 of the member 40.

The projection 34 is adapted to receive a clamping member 53 which may be of any suitable form, the pressure between the clamps being obtained by the screws 54, so that when the members 36 and 37 are slidably adjusted within the projection 34, the same may be locked securely in position. As will be seen, this adjustment of the lamp bulb 38 within the reflector may be readily obtained by loosening the clamp 53 and tak-

ing hold of the yoke 41 and moving the complete yoke structure. The bracket members 32 and 33 have a certain amount of resilience so that when the unitary structure herein described is mounted within the casing, the effect is that of a spring pressed connection against the front of the lamp casing. 70

While I prefer to assemble the packing 29 in the manner illustrated in the drawing, it may, of course, be attached to the front 75 part of the casing and cooperate with the shell and reflector to close the front opening into the reflector.

Other changes in the details may of course be readily brought about without departing from the spirit of my invention or the scope of the appended claims. 1

Having thus described my invention what I claim is:

- 1 claim 1.

  1. In combination, a casing having a transparent member mounted in the front thereof, said casing having at least one fixed and one adjusting anchorage means, a reflector, a shell carrying the reflector, a ring attached to the shell and having a part engaging the edge of the reflector for holding it in position within the shell, cushioning means co-operating between the shell, ring and front of said casing to insure a substantially tight joint around the front part of the reflector, at least, two metal members attached to the shell, one of said members engaging said fixed anchorage and the other said adjusting anchorage on the casing, a lamp socket carried by said shell and adapted to carry a lamp within said reflector. 85
  2. In combination, a casing having a transparent member mounted in the front thereof, a reflector, a shell carried by the reflector, a ring attached to the shell and having a part engaging the edge of the reflector for holding it in position within the shell, cushioning means co-operating between the shell, ring and front of said casing, to insure a substantially tight joint around the front part of the reflector said casing having a fixed anchorage at the bottom of the casing and a pivoted screw threaded anchorage at the top, a pair of forked metal members attached to the shell at substantially diametrically opposite points, one of said forked members engaging said fixed anchorage and the other said screw threaded anchorage whereby the cushioning means may be drawn tightly against said casing front, a lamp socket carried by said shell and adapted to carry a lamp within said reflector. 105
  3. In combination, a casing having a transparent member mounted in the front thereof, and a unitary structure carried within the casing for emitting light through said transparent member, said unitary structure comprising; a reflector, a shell carrying the reflector, a ring, resilient packing means be- 125

tween the ring and edge of the shell and normally extending beyond both, means for holding the ring and packing means in proper relation to the shell and reflector, members attached to the shell for mounting it within said casing, said shell having an extending part, and a lamp mounting ad- justably carried by said extending part, said lamp mounting including a yoke on its outer end, said yoke carrying contacts with ¹⁰ means for engaging members contacting with the terminals of the light bulb.

In testimony whereof, I affix my signature.

LEON S. BRACH.
